ARCH SUPPORT

Max Sadler, Providence, R. I., assignor to Capitol
Heel Lining Company, Providence, R. I.

Application June 23, 1932. Serial No. 618,973

1 Claim. (Cl. 36—71)

This invention relates to supports for the feet and particularly it relates to arch supports provided with a protective sheathing.

A great variety of arch supports have been placed on the market. In general they are comprised of a metal plate which is shaped so as to support the foot in its normal position. In most instances this metal plate only supports the arch of the foot and does not extend to the heel and toes. Moreover, the metal plate is usually covered by a leather piece so as to prevent direct contact with the foot.

Most of these devices now on the market are subject to several disadvantages. One of these disadvantages is that the sharp edge of metal plate cuts the side of the shoe and thereby causes damage to the same. Another disadvantage is that the metal plate, even though provided with a leather covering, is most uncomfortable when worn for any length of time. I am aware of several attempts to remedy these situations, but in all such instances either the comfort qualities were not increased materially, or, if they were increased, the supporting qualities of the support were rendered ineffectual.

One of the objects of my invention is the provision of an arch support which will not cause injury to the shoe or to the wearer.

Another object of the invention is the provision of an arch support having a protective sheathing.

The invention has for a further object the provision of an arch support which furnishes excellent support and at the same time is very comfortable to wear.

A still further object is the provision of an arch support which may be easily and inexpensively manufactured.

Further objects will become apparent from a reading of the following description and drawing.

40 In the drawing:

Fig. 1 is a plan view of the bottom of my novel arch support.

Fig. 2 is a plan view of the bottom of a modification on my support.

45 Fig. 3 is a cross-section view on the line III—III of Fig. 2, and,

Fig. 4 is a cross-section view on the line IV—IV of Fig. 2.

50 As shown in the figures, my improved arch support is comprised of a stiffened plate 2 of thin but rigid metal which has been pressed or stamped into a shape to properly support the foot in normal position and particularly the arch of the foot. This plate 2 is preferably provided with

an arc-shaped strengthening ridge 4 which aids materially in maintaining the plate in its original pressed form.

The plate 2 is adapted to be worn between the insole of a shoe and the foot of the wearer. It does not, however, contact directly with the foot of the wearer since it is provided with a flexible covering 6, which may be of leather or other suitable material. The flexible covering 6 is larger than the plate 2 and is comprised of a heel portion 8, a shank portion 10, and a forward portion 12. It is secured to the plate 2 by means of eyelets 14 or by any other suitable means.

In the past considerable trouble, annoyance, and expense has been caused in similar arch supports for the reason that the edges of the plate, and particularly the marginal edge 16, would cut into the side of the shoe and damage it. In my novel construction this disadvantage is obviated by providing a protective sheathing 18 which completely covers the under side of the marginal edge 16. As illustrated in Fig. 1, this protective sheathing 18 may be secured to the under side of the plate 2 by the same eyelets 14 which are used to secure the flexible covering 6 to the plate.

The protective sheathing 18, in addition, is also preferably held in place by stitching 20 which secures it to the flexible covering 8. This arrangement has been found most satisfactory since it renders it impossible for the protective sheathing 18 to work or slide out of place so as to permit the edge 16 to become exposed. Therefore, it is impossible in this arrangement for the marginal edge 16 to damage the shoe in any way.

It has also been noted that many of the arch supports now available on the market, while they may satisfactorily support the arch, are very uncomfortable especially if worn for any length of time.

In Figs. 2, 3 and 4, I have shown an arrangement in which the supporting qualities of the support are in no way impaired, while at the same time perfect comfort is insured at all times. The plate 2' in this modification is provided with a depressed portion 22'. Since Fig. 2 is a plan view of the bottom of the device, both this depressed portion 22' and the ridge 4' appear raised in that figure. This depressed portion 22' serves as a pad receiving pocket. Any suitable pad (not shown), for example, one constructed of felt, sponge rubber or the like, may be placed in depressed portion 22' simply by raising the edge 24' of the flexible covering 8' to permit the pad to be inserted. This arrangement has been found to provide a maximum amount of com-

fort to the wearer and at the same time it does not detrimentally affect the supporting properties of the arch support.

The complete structure may be simply manufactured and assembled. The arrangement is rugged and will out-last several pairs of shoes. Nor will it damage the shoe in any way. At the same time it very efficiently performs its function as a support and affords real comfort at all times.

Having now described my invention, what I claim as new and desire to secure by Letters Patent of the United States is:

An arch support comprising a substantially rigid thin metal plate formed to support the longitudinal arch of a foot in its normal position,

said plate being provided on its inner side with an outwardly curving arc-shaped depressed strengthening ridge merging into a depressed centrally located pad-receiving recess, a flexible covering secured to the upper side of said plate at points spaced from said recess whereby the flexible covering may be lifted to permit a pad to be inserted in said recess, and an arc-shaped protective sheathing secured to the under side of said plate for covering the inner edge thereof when the plate is being worn, the inner edge of said sheathing when in secured position being disposed to abut against said strengthening ridge, whereby said ridge aids in maintaining the sheathing in correct position.

MAX SADLER.
